UNITED STATES PATENT OFFICE.

REGINALD JOHN PAGE, OF AUCKLAND, NEW ZEALAND, ASSIGNOR OF ONE-HALF TO
JOANNA DICKSON AND ONE-FOURTH TO HARRY CLINTON McELWAIN, BOTH OF
AUCKLAND, NEW ZEALAND.

DOMESTIC FIRE GRATE.

Application filed June 3, 1925. Serial No. 34,705.

To all whom it may concern:

Be it known that I, REGINALD JOHN PAGE, a citizen of the United States of America, residing at Auckland, in the Dominion of 5 New Zealand, have invented certain new and useful Improvements Relating to Domestic Fire Grates, of which the following is a specification.

This invention relates to fire grates for 10 room warming purposes, and has for its object the provision of improvements which relate to fire grates of the type capable of being rotated about their vertical axes within chimneys to cause them to face towards or 15 into either one of a pair of adjoining rooms at opposite sides of a chimney, the latter having a single flue and a lower portion containing a cross passage extending completely through it from room to room, openings being provided through the walling of the 20 respective rooms at each end of said cross passage.

The main improvement provided by the 25 invention, consists in the provision of shutters, and frames operable vertically in guides at each end of the chimney cross passage in order that the latter may be completely closed at both ends, or be completely closed at the end in or towards which the back of 30 the grate is located, or faces, while a frame at the other end of the cross passage may be utilized to fill up the space not occupied by the grate front.

Other improvements consist in the construction and mounting of the grate, and in the provision of means for rotating same.

The fire grate is mounted on a platform supported on a ball pivot held in a socket situated below the centre of the flue in the 40 upper portion of the chimney.

The fire grate is provided with a short tubular uptake flue which is entered in and is capable of being rotated within the lower end of the chimney flue.

The platform on which the fire grate is mounted is capable of being turned through a horizontal plane in order to cause the front of the fire grate to face towards or into either of the adjoining rooms as required.

The means for causing the fire grate to be turned to face into either of the adjoining

rooms, consists of bevel gears and shafts operable from either room.

The invention will be further described in conjunction with the accompanying drawing, wherein:

Figure 1 is a cross sectional elevation of the improved fire grate and a chimney and walling, and

Figure 2 is a sectional elevation of same viewed from one side, and with the walling of the room at that side removed,

Figure 3 is a sectional plan view of the fire grate and parts shown in Figure 1.

Figure 4 is a similar view to Figure 1 but showing the grate half turned and all the shutters and frames raised,

Figure 5 is a sectional plan view of the parts as shown in Figure 4.

The brick work 1 of a single flue chimney 70 is located in the wall space between a pair of adjoining rooms, the lower portion of the chimney being formed to provide a cross passage 2, extending completely through it from one of said rooms to the other room, 75 openings in the wallings of said rooms being provided at the ends of the cross passage 2, and being surrounded by the usual mantels 3.

A fire grate 4 is mounted on a platform 5, 80 the latter being centrally supported on a ball pivot 6 held in a socket 7 in the floor at the bottom of the chimney.

The fire grate 4 is provided with a tubular uptake flue 7^a which is entered in and capable of rotation within the lower end of the flue 8 of the chimney. The uptake flue 7^a of the fire grate 4 is positioned directly above the ball pivot 6 on which the platform 5 is supported, thereby providing that the 90 platform 5 together with the fire grate 4 on it may be rotated about a vertical axis and through a horizontal plane as required, in order to cause the open or front face of the fire grate 4 to face into or towards either 95 one of the adjoining rooms.

Ball castors 9 or the like can be provided on the underside of the platform 5 and are adapted to run on the floor surface beneath the said platform, in order to ensure that 100 the latter and the fire grate 4 thereon can be easily rotated on the ball pivot 6.

Frames 12 slidable vertically in guides 12^a at the sides of the wall openings, at the ends of the cross passage 2 are used one at a time to close the spaces at the sides and top of the 5 fire grate 4, between the latter and the edges of the mantel 3 at the front or open face of said fire grate.

The shutters 10 are slidable vertically in 10 guides 11 in the frames 12 and are capable of being drawn down one at a time and with a frame 12 to completely close the space in a wall surrounded by a mantle 3 so as to screen off or obscure from view the back of the fire grate 4 in that room towards which 15 said back is for the time being facing, or both of said shutters 10 and both frames 12 can be drawn down to close the spaces within both mantels, so as to hide the grate 4 from view from both rooms when the grate 20 is not in use.

A frame 12 when drawn down at the front of the grate 4 prevents draught through the cross passage 2 to the flue 8 in the chimney and diverts all draught through 25 the grate 4, as well as making the front or open face of the fire grate appear neat and tidy when viewed from the room towards which it is facing, and upon the shutter 10 at that side being raised.

30 In Figures 1 and 3 of the accompanying drawing, the fire grate 4 is shown with its open or front face presented to one of the pair of adjoining rooms. In this position the shutter 10 at the back of the fire grate 4 is drawn down and the frame 12 at the same side is also drawn down, the combined shutter and frame completely closing the space within the mantel 3 to screen the back of the fire grate from view.

40 The shutter 10 at the front or open face of the fire grate 4 is raised to its uppermost position, thereby exposing the open face of the said fire grate to view in the room towards which said grate is facing, the frame 45 12 at that side however being drawn down to close the spaces at the sides and top of the fire grate between the latter and the edges of the mantel 3.

The shutters 10 and frames 12 at both 50 sides of the chimney are preferably counterbalanced by means of cords 13, pulleys 14 and weights 15 in the well known manner employed in hanging sliding window sashes.

55 When it is desired to rotate the fire grate 4 on its pivot 6 to cause its open or front face to be presented to the opposite room to that which it has previously been facing, the shutters 10 and frames 12 at both sides of the chimney are raised so as to render the 60 passage or space 2 through the chimney unobstructed at its ends.

The platform 5 and the fire grate 4 thereon are then rotated on the pivot 6 until the front of the fire grate 4 is presented to the 65 desired room, the shutter 10 and frame 12 at

the back of the grate, and the frame 12 at the front of the grate being then drawn down.

By reason of the fact that the size of the apertures at the ends of the cross passage 2 are restricted by the said frames 12 and shutter 10, insufficient room is provided for the platform 5 to be rotated on its pivot 6 so long as the shutter 10 and frames 12 are down, and the fire grate 4 is thereby held 75 facing the desired room.

If desired, mechanical means can be provided for rotating the platform 5 and fire grate 4 on the ball pivot 6, such means preferably comprising a bevel gear 16 secured 80 around the uptake flue 7^a of the fire grate 4, a further bevel gear 17 meshing with the bevel gear 16 and secured on one end of a short shaft 18, a bevel gear 19 on the other end of the shaft 18 meshing with a bevel gear 20 keyed centrally on a shaft 21 adapted 85 to extend through the cross passage 2, so that its ends are accessible, from the adjoining rooms, said ends being suitably squared or otherwise formed to take a handle or crank whereby said shaft 21 can be rotated when required to cause the fire grate 4 to be rotated.

In a modification the shutters 10 instead 90 of working in guides 11 in the frames 12 may be extended to work in the same guides 12^a as the frames 12 and in front of the latter, in which case said frames 12, will only be used for closing spaces at the top 95 and sides of the open face of the fire grate 4. 100

What I do claim and desire to obtain by Letters Patent of the United States of America is:—

1. A fire grate of the kind described revolvable about a vertical axis in a cross passage in chimneys so as to be capable of being made to face into either of two rooms; shutters and frames operable vertically in guides at each end of said passage to completely close one end of said passage and partly close the other end thereof, or to completely close both ends of said passage, substantially as described and illustrated. 105

2. A fire grate according to claim 1, where-in said frames operate in vertical guides in walling, and said shutters in guides in the frames, substantially as described and illustrated. 115

3. A fire grate, according to claim 1, where-in said frames and shutters are counterbalanced and are each operable independently of the others, substantially as described and illustrated. 120

4. A fire grate according to claim 1 where-in said frames and shutters are counterbalanced and are each operable independently of the others, said shutters operating in the same guides as, and on the outside of, said frames, substantially as described and illustrated. 125 130

5. A fire grate according to claim 1, wherein said grate is revolvable on a central ball pivot and has an uptake flue which is entered in the flue of the chimney, substantially as described and illustrated.

6. A fire grate, according to claim 1, wherein said grate is mounted on a platform re-

volvable on a central ball pivot and rollers, said grate having an uptake flue which is entered in the flue of the chimney, substantially as described and illustrated. 10

In testimony whereof, I have signed my name to this specification.

R. J. PAGE.
